(57) **CLAIM**

What is claimed is the ornamental design for a skin care applicator tip with a hatch, as shown and described.

DESCRIPTION

FIG. 1 is a perspective view of a skin care applicator tip with a hatch according to the present invention;

FIG. 2 is a front view of the skin care applicator tip according to the present invention;

FIG. 3 is a rear view of the skin care applicator tip according to the present invention;

FIG. 4 is a side view of the skin care applicator tip according to the present invention;

FIG. 5 is a side view of the skin care applicator tip according to the present invention;

FIG. 6 is a top view of the skin care applicator tip according to the present invention; and,

FIG. 7 is a bottom view of the skin care applicator tip according to the present invention.

The broken lines in the drawing depict parts of a skin care applicator tip with a hatch that form no part of the claimed design.
